(57) CLAIM

I claim the ornamental design for a hair brush body, as shown and described.

DESCRIPTION

FIG. 1 is a front perspective view of a hair brush body, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof; and,

FIG. 9 is another front perspective view thereof, showing brush bristles that form no part of the claimed design. The broken lines in the drawings show environment only and form no part of the claimed design.
